UNITED STATES PATENT OFFICE.

JACOB BATCHELDER, OF SALEM, MASSACHUSETTS.

SOLE-CUTTING MACHINE.

Specification of Letters Patent No. 23,889, dated May 10, 1859.

To all whom it may concern:

Be it known that I, JACOB BATCHELDER, of Salem, county of Essex, Commonwealth of Massachusetts, have invented a new and 5 useful Antifriction Boot and Shoe Sole Cutting Machine; and I do hereby declare that the following is a full and exact description thereof, reference being had to the accompanying drawings and to the letters of reference marked thereon.

To enable others skilled in the art to which my invention belongs, to make and use the same, I will proceed to describe its construction and operation.

15 Figure 1, of the drawings represents a vertical section through the center of the machine; Fig. 2, a front view of the machine; Fig. 3, a front view of one of the knife frames; Fig. 4, a bottom view and 20 Fig. 5, a top view of the same knife frame; Fig. 6, a top view and Fig. 7 a bottom view of the other knife frame.

The knives a , and a' , are of such a shape as to correspond to the outline of a boot or 25 shoe-sole, as will be seen from Figs. 4, and 7. They are mounted on bars b , b' , which are pivoted to frames c , c' , at d , and d' . These pivots d , and d' , are about halfway 30 between the ends of each bar, while near the ends set screws h ', h ', and s ', s ', project from the bars upward and through slots in the frames c , c' . By this means it will be seen, the knife bars can be turned on their pivots d , d' , and be fastened by the use of 35 the set screws. The object of this arrangement is to cut differently shaped soles with the same pair of knives. The knife bar b' , allows of another adjustment for the same purpose, by means of the thread of the adjusting screw i' , taking into corresponding 40 screw threaded-notches in the end of the bar, as seen at j' , Fig. 4.

The knife frames c , c' , are fastened to two upright levers each and these levers 45 e , e , and e' , e' , are hung to two cranks each. The levers e , e , are hung to cranks n , f , two of these cranks on each side of the machine; the cranks n , being pivoted to the levers at n' , and to the frame v , of the machine at 50 points n'' , the latter being the fulcra of the cranks. The lower ends of the levers e , e , are connected to cranks f , f , extending from the main shaft j . The levers e' , e' , of the other knife frame are similarly hung 55 to cranks p , and f' , as shown in the draw-

ings. Each lever e' , is pivoted to crank p , at p' , the crank being fulcrumed at p'' , and the lower end of each lever e' , is connected to a crank f' , extending from shaft j . Flywheels x , x' , are fastened to the ends of shaft j . A block s , is provided with a pin r ', which passes through a hole in the rail t , of the machine frame. The block can thus be adjusted at a greater or less distance from the rail and can be fastened in any of 60 its positions by means of a set screw u . A board w ', is supported by two springs g , fastened to the under side of table w , and curved up at m , as represented in Fig. 1. A screw r , passes through the center of the 70 board w ', and by turning the screw its end can be made to project more or less beyond the board w ', and toward the table w . The block s , and screw r , serve as stops for the front edge of the leather while being cut by 75 the knives a , and a' , respectively. A little pin i , projects from one end of the board w '; a spring l'' , abruptly bent at l , and ending in a hook l' , is secured to the frame of the machine at its lower end, at y'' ; and a 80 pin o , extends from the lever n .

The relative functions of the last mentioned parts of the machine will be understood from the operation of the machine now to be described. Suppose the parts of the machine to be in the position represented in the drawings, a piece of leather being placed on table w , with its front end abutting against stop r . If shaft j , is now revolved in the direction of arrows i , i , the knife a , will rise 90 above its present position, while the knife a' , descends and cuts through the leather. When the shaft has been revolved so far that the cranks f , f' , stand vertical, the knife a' commences to rise from the leather and the 95 knife a , begins to descend toward the leather. During the ascent of knife a , the pin o , on crank n , came in contact with the curved part l , of the spring l'' , pushing the spring back toward the machine-frame, until the 100 hook l' , at the upper end of the spring slipped from the pin i , at the end of board w ', and thus allowed the board to follow the tendency of its supporting springs g , g , and to rise upward. The leather is now clear of stop r , and of the under edge of board w ', and can be pushed forward until its edge meets the stop s . During the descent of the 105 knife a , and about the time it comes in contact with the leather the pin h , extending 110

from the frame of knife *a*, meets the supporting spring *g*, and depresses it and the board *w'*, together with it until the pin *i*, 5 slips under the hook *l'*, thus placing the stop *r*, again in line with the leather, which in the mean time has received the second cut. The descent of the board *w'*, serves at the same time the purpose to push down the portion of the leather cut off by the second 10 cut. The leather can now be pushed forward until its front edge abuts against stop *r*, and if the shaft *j* is further revolved the above described operation will be repeated. 15

It will be seen that by adjusting the stops *r*, and *s*, at different distances from each other, and their respective knives soles of various widths can be cut, without changing the knives or their relative positions. It 20 will also be seen that the knives being hung on pivots and thus axial friction being sub-

stituted for sliding friction, the power consumed by friction, will be extremely little.

Having described my antifriction boot and shoe sole cutting machine, what I claim therein as new and of my invention and desire to secure by Letters Patent, is:

1. The particular and relative arrangement of the levers *e*, *e*', *e'*, *e'*', with the cranks *n*, *p*, and *f*, *f'*, for giving the required motions to the cutting knives as herein set forth.

2. The use and arrangement of the adjustable and intermediate gage board *w'*; as described, whereby each alternate sole can be cut of equal or unequal width as set forth.

JACOB BATCHELDER.
